HEATING BY MEANS OF SOLID FUEL OF
VERY SMALL SIZES

Aimé Vandevelde, Brussels, Belgium

Application February 23, 1933, Serial No. 658,220
In Belgium September 22, 1932

25 Claims. (Cl. 122—4)

The invention has relation to the heating by means of solid fuel and concerns particularly the heating by means of domestic fires and the central heating for buildings and the like.

6 The main object of the invention is to enable coals of very small sizes, that is to say of the order of 5 to 10 m. m. and less to be used for this purpose, and particularly coals of reduced contents in volatile matters.

10 The invention consists in forming the heating source by means of a bed or layer of said fuel in which are formed a number of firing and gas forming centers by blowing therein air under pressure, the said blowing being effected horizontally but preferably vertically downward or in an inclined downward direction, that is to say in the direction or approximately in the direction of the natural fall of the fuel.

15 The invention also consists in forming the blowing device by means of a nozzle or groups of nozzles, which nozzles may be arranged at different levels, such nozzles being water cooled either individually or in groups by locating said groups in water chambers of the apparatus.

20 The invention further consists in maintaining a certain thickness of fuel, for example of a few centimeters height above the upper blowing nozzles, preferably as by means of a continuous gravity feed.

25 The invention further consists in so arranging the fuel supply that the coal is fed in the same direction as the blowing air that is to say from the same side that the air relative to the slags which may be formed during combustion.

30 And in order that the invention may be easily understood it will be now described with more details in reference to the annexed drawings showing by way of example the invention as applied to an apparatus for central heating purposes.

35 In these drawings:

Fig. 1 is a diagrammatical cross sectional elevation view of a boiler for central heating purposes provided with a fire-box embodying the invention.

40 Fig. 2 is a longitudinal sectional elevation of the boiler.

Fig. 3 shows in sectional elevation a modification of the fire box.

45 Fig. 4 is a part detail view.

Fig. 5 is a sectional view along 5—5 Fig. 6, and Fig. 6 is a longitudinal sectional view, through a boiler provided with a central blowing device.

50 Fig. 7 is a side elevation and Fig. 8 a sectional view through 8—8 Fig. 7 of a modified construction of the blowing device.

Referring to Figs. 1 and 2, the boiler which may be of circular, rectangular or any other shape has been illustrated in a conventional manner as comprising a water chamber 1 and a fire box 2, but it is to be understood that the arrangement might be different and of any known design. The fire box 2 is connected to the usual chimney (not shown) through the conduit 42 provided with a damper 43.

The said fire box 2 is provided with a pair of 10 water jacketed walls 3 leaving a space 4 between them and bounding air chambers such as 5. The water partitions 3 are connected in the water circuit of the boiler through junction pieces 6 and 7 so as to be fed by the water at the lowest temperature.

15 Between the air chambers 5 and the space 4, nozzles such as 8 and 9 are provided, said nozzles being illustrated of cylindrical shape, but they may be as well of conical, flattened or other suitable shape.

20 These nozzles 8 and 9 are arranged at different levels and are of different cross sections but all the said nozzles are inclined downwardly that is to say in the direction of the natural fall of the 25 fuel.

25 The air chambers 5 are connected together as at 10 and supplied with air under pressure introduced therein by means of a pipe 11 illustrated as connected to the fan 12 operated through an electrical motor 13. However this pipe could also be connected to any other supply source of compressed air provided with a suitable shutter or the like.

30 The pipe 11 is provided with a control valve 14 for adjusting the air flow therein.

35 The inner surfaces 15 of the water partitions 3 are sloped outwardly to a small extent to enlarge somewhat the space 4 in downward direction and either in or on the surfaces 15 guide members 16 have been provided for the purpose explained later on.

40 Above the space 4 of the fire box 2 is arranged a fuel distributor 17, the mouth piece of which extends along the major axis of the space 4, but is of smaller length than said axis.

45 The mouth piece 17 is connected through a conduit 18 of comparatively large section to a fuel hopper 19 arranged at a suitable location and for example at the top of the boiler.

50 A shutter 44, preferably of the rotating type as illustrated, is provided at the lower end of the conduit 18.

55 20 designates a thermostat device and if desired a thermometer 21 may be provided, the

thermostat device controlling a switch 22 inserted in the supply circuit 23 of the electric motor 13.

Should the chambers 5 be supplied with air 5 under pressure from any other source than the fan 12, then the thermostat device 20 is arranged to control the shutter of the said source.

The arrangement is completed by means of a plate 24 closing the bottom of the space 4, said 10 plate sliding on the lower guide members 16 on the surfaces 15 above the usual ashpit 25, and a plate 26 (Fig. 4) is provided and adapted to engage on the upper guides 16 and to be operated as hereafter explained.

15 In Figures 5 and 6, 1 and 2 again designate the water chamber and the fire box respectively, illustrated in a conventional manner. The fire box 2 is connected to the chimney by means of the conduit 42 provided with a damper 43.

20 A trough like member 45 is provided in the fire box 2, the sides and the bottom of said trough having been illustrated as formed by means of a solid plate, but these sides and bottom could be formed as water partitions and connected in the water circuit of the boiler as those designated by the reference number 3 in Figs. 1 and 2.

The sides of the trough 45 show a marked downward slope, approximating the natural 25 slope of the coal, a slope such as 45° being suitable for coals of 5-10 mm. as sizes.

The bottom of the trough may be solid with the sides thereof as illustrated or it may be formed as a detachable member removable by 30 means of a longitudinal sliding movement.

A gap 52 may be provided all around the upper edge of the trough or on a part of said edge only for the admission of auxiliary combustion air.

Above and at some distance from the bottom 40 of the trough 45 there is provided a blowing device comprising a pear like section conduit 46 having a slot 47 formed therein and surrounded by a casing 48, the intermediate space 49 being divided into two compartments communicating 45 together at one end and forming a water chamber.

The end of the conduit 46 is connected through a conduit 11, provided with a closing member 14, to the pressure side of the fan 12 operated through 50 the electric motor 13 under control of a thermostat device 20 and a switch 22 as in foregoing example.

The casing 48 is connected, through the pipes or conduits 35 and 36 to the water circuit of the 55 boiler, the outlet of the casing being connected to the hot water main 28. However the casing 48 may be arranged as a separate water circuit.

Also the blowing device may be arranged as 60 illustrated in Figs. 7 and 8 in which case the air under pressure is supplied through a conduit 29 provided with a slot 50 in the lower part thereof and distributed through two lateral slots 47 sloping in downward direction, and formed between a lower conduit 30 and two upper conduits 31 65 adjacent the conduit 29, the conduits 30 and 31 being connected to a box 32 and the conduits 31 being connected to a box 33 provided with a junction member 34. The box 32 is arranged so as to avoid the formation of a vapor chamber 70 therein and a conduit 51 connecting the box 32 to the connecting member 34 may be provided for that purpose.

A soldered connection is formed between the 75 conduits 29 and 31 and the cooling water enters

the conduit 30 and escapes through the conduits 31 and the box 33.

Above the blowing device within the firebox 2 there is provided a fuel distributing member 17, extended in the direction of the major axis of the fire space 4, the distributing member 17 being provided with a rotating shutter 44 and supplied in fuel through a conduit 18 of comparatively large section connected to a hopper 19 arranged at the top of the boiler. A thermometer 10 21 completes the arrangement.

The operation is as follows:

The hopper 19 being filled up with coals of small sizes, and for example with coals of 5-10 mm. of relatively small content in volatile matter, this fuel falls by gravity through the distributor 17 and forms a bed in the space 4 or in the trough 45, up to a few centimeters, above the upper nozzles 8 (Figs. 1 and 2) or the slots 47 (Figs. 5 and 6).

The fire then being started, the motor 13 is operated and the air passing through 8 (Figs. 1 and 2) or 47 (Figs. 5 and 6) forms in the vicinity of these nozzles a number of active combustion and gas forming centers, while the remainder of the bed slowly enters in more or less marked combustion, the combustion of the formed gases being completed above the bed partly with the aid of the air passing through 8 and 47 and partly by means of air passing through 9 (Figs. 1 and 2) or 52 around the trough 45 (Figs. 5 and 6).

In Figs. 1 and 2 the air passing through the nozzles 9 is intended to insure the combustion of the fuel having passed the zone of the combustion centers of the nozzles 8 without being completely burnt out, but such nozzles may not always be required or also they may form more or less active combustion or gas forming centers.

The combustion products escape to the chimney 40 through the conduit 42, the damper 43 of which is suitably adjusted for that purpose.

When the temperature of the water in the boiler raises the point of adjustment of the thermostat device, said thermostat device operates to 45 open the switch 22 and stops the electric motor 13 and the blowing of the air. Under such circumstances, a state of slow combustion succeeds to the activity of the combustion and gas forming centers, said slow combustion remaining insured by means of the small draught through the passage in the conduit 42 adjusted by the damper 43, the combustion air passing through the fan, conduit 11, chambers 5, and nozzles 8 and 9 in Figs. 1 and 2 or through the fan, conduit 11 and 55 the slot 47 in Figs. 5 and 6.

This slow combustion state remains established as long as the temperature of the boiler does not drop below that for which the thermostat device 20 has been adjusted.

When this limit is reached the thermostat device actuates the switch 22, operating the electric motor 13 and the fan 12, restoring in a very short time the activity of the combustion and gas forming centers.

Owing to the nature of the coals used and in view of the high temperatures attained during the combustion operation, slags are liable to form, which however are easily removed.

In the Figs. 1 and 2 the plate 26, the forward edge of which is indented, or any other similar member, is used for that purpose, said member being engaged in the fuel bed, upon closure of the shutter 44, by sliding it on the upper guides 16 as indicated in dotted lines in Fig. 2.

The slags are either raised above the fuel bed and thereupon easily removed through the usual loading opening of the fire box, or broken to pieces and carried along in the free space 27 previously served at the rear end of the fire box, and thence transferred to the ash-pit 25 by some forward movement of the plate 24.

If at the time cinders are to be removed from above the plate 24, the latter is wholly removed and again inserted before the plate 26 is removed.

In the arrangements in accordance with Figs. 6 and 7, the slags which may have been formed are located opposite the air jet or jets and, or on either side of the blowing device but in view of

the fact that the fuel supply is located on the same side as the air supply relative to these slags, the fresh fuel is always supplied in zones through which the air passes with the result that no adjustment of the blowing pressure is required during the growth of the slags and that a regular combustion is obtained whatever period the fire has been operated without removal of the slags. Other things being equal the fan may thus be less powerful.

The slags are easily removed by means of tongs or any other device through the loading door of the fire box.

In the embodiment according to Figs. 1 and 2, the water partitions 3 and the chambers 5 are arranged as parts of the fire box 2, but it remains within the limits of the invention to construct the partitions 3, chambers 5, nozzles 8 and 9, conduits 10 and the junction members as a separate structure adaptable to existing fire boxes, the supply conduit 18 entering the fire box 2 either through the loading door or through the top part of the boiler.

In Fig. 3 the arrangement of fire box 2 is similar to that of the preceding figures but the surfaces 40 of the water partitions 3 are of step formation, thus reducing the width of the bed at the level of the nozzles 9 and providing guides 16 for the plates 24 and 26.

The reduction of the width at the bottom part of the bed tends to prevent the fuel to pass through the zone of the nozzles 8 without being burnt therein and enables the number and cross sectional area of the nozzles 9 to be reduced and even these nozzles to be dispensed with.

In this example the chambers 5 are in the form of conduits arranged in the water partitions 3.

Nozzles delivering secondary combustion air above the upper level of the fuel bed may be provided if desired.

Although the invention has been particularly described as applied to boilers for central heating purposes, it is to be understood that it is not limited to such boilers. When applied to heating apparatus of the ordinary type, instead of being controlled by the temperature of the water in the boiler, the thermostat device would be operated by the temperature of the space to be heated.

I claim:

1. A heating device comprising a heating source formed with an open topped trough having a non-perforated bottom adapted to contain a bed of small sized coals, downwardly directed nozzles arranged with their delivery ends below the upper level of the trough, water cooling means associated with said nozzles, said cooling means extended to the delivery ends of the nozzles, gravity coal supplying means located above the trough and delivering coal in the trough and means to supply said nozzles with air under pressure.

2. A heating device comprising a heating source

formed with an open topped trough having a non-perforated bottom adapted to contain a bed of small sized coals, downwardly directed nozzles arranged with their delivery ends within the trough and at a distance below the upper level thereof, water cooling means associated with said nozzles and extending to the delivery ends thereof, coal delivery means extended in downward direction to the vicinity of the upper level of the trough whereby the coal is delivered by gravity to said trough, means to supply air under pressure to the nozzles and means to obturate the fuel supply means.

3. A heating device comprising a heating source formed with an open topped trough having a non-perforated bottom adapted to contain a bed of small sized coals, downwardly directed nozzles arranged with their delivery ends within the trough and at a distance below the upper level of said trough, water cooling means associated with the nozzles and extending to the delivery ends thereof, coal feeding means in the form of a descending conduit with a delivery mouth located in the vicinity of the top level of the trough and extended along the major axis of said trough, a rotating shutter adjacent the delivery end of the descending conduit, and means to supply air under pressure to the nozzles.

4. A heating device comprising a heating source formed with an open topped trough adapted to contain a bed of small sized coals, downwardly directed nozzles arranged with their delivery ends within the trough and at a distance below the upper level of said trough, water cooling means associated with the nozzles and extending to the delivery ends thereof; coal feeding means in the form of a descending conduit with a delivery mouth located in the vicinity of the top level of the trough, means to supply air under pressure to the nozzles whereby air issued

therefrom passes through the inner space of the trough, the coal feeding means located so that the coals are delivered therefrom in the same direction as the air from the nozzles.

5. A heating device comprising a fire box formed as an open topped trough like member having a nonperforated bottom and downwardly sloping walls adapted to contain a bed of small sized coals

the upper level thereof approximating the upper level of said walls, water cooled air supply nozzles, said nozzles having their mouths a few

centimeters below the upper level of said walls, and said nozzles directed in downward direction, gravity coal supplying means delivering the coals in the vicinity of the upper level of the trough,

a shutter and an enlarged delivery mouth for said coal supplying means and said last named mouth extended along the major axis of the trough, means to supply air under pressure to the nozzles.

6. A heating device comprising a fire box formed of a comparatively shallow trough like member having a nonperforated bottom and downwardly sloping walls adapted to contain a bed of small sized coals with the upper level thereof approximating the upper level of said walls, water cooled air supply nozzles having their mouths directed in downward direction and located centrally of the trough, gravity coal supplying means, a shutter and a delivery mouth for said coal supplying

means, and said last named mouth located centrally of the trough, means to supply air under pressure to the nozzles.

7. A heating device comprising a fire box formed as a trough like member having a nonperforated

- bottom and downwardly sloping walls adapted to contain, a bed of small sized coals with the upper level thereof approximating the upper level of said walls, water cooled air supply nozzles having their mouths directed in downward direction and within the inner space of the trough below the upper level thereof, said nozzles located along the major axis of the trough, gravity coal supplying means, a shutter and a delivery mouth for said coal supplying means, said last named mouth extended along the major axis of the trough and just above the air supply nozzles, means to supply air under pressure to the nozzles.
8. A heating device comprising a fire box formed as a trough like member having a nonperforated bottom and downwardly sloping walls, adapted to contain, a bed of small sized coals, water cooled air supply nozzles having their mouths directed in downward direction and delivering within the inner space of the trough, gravity coal supplying means located above the trough and delivering coal in the vicinity of the upper level of said trough, air passages having their mouths above the upper level of the trough, means to supply air under pressure to the first named nozzles, means to supply air to the said passages, and heat controlled means to control the supply of pressure air to the nozzles.
9. A heating device comprising a fire box formed as a trough like member having a nonperforated bottom and downwardly sloping walls adapted to contain, a bed of small sized coals, water cooled air supply nozzles having their mouths directed in downward direction and delivering within the inner space of the trough, said nozzles arranged centrally along the major axis of the trough, gravity coal supplying means located above the trough and delivering coal in the vicinity of the upper level of said trough, a shutter and a delivery mouth for said coal supplying means, said last mouth extended centrally along the major axis of the trough and just above the nozzles, and means to supply air under pressure to the nozzles.
10. A heating device comprising a fire box formed as a trough like member having a nonperforated bottom, a combustion chamber above said trough, nozzles arranged with their delivery ends within the trough, means for delivering fuel to the trough from above said trough, and means for supplying the nozzles with air under pressure.
11. A heating device comprising a fire box formed as a trough like member having a nonperforated bottom, nozzles arranged with their delivery ends within the trough, means for the continuous delivery of fuel to the trough from above said trough, and means for supplying the nozzles with air under pressure.
12. A heating device comprising a fire box formed as a trough like member having a nonperforated bottom, a combustion chamber above said trough, nozzles arranged with their delivery ends within the trough, means for delivering fuel by gravity to said trough, and means for supplying the nozzles with air under pressure.
13. A heating device comprising a fire box formed as a trough like member having a nonperforated bottom, nozzles arranged with their delivery ends within the trough, means for the continuous delivery of fuel to the trough from above said trough, means for supplying the nozzles with air under pressure, and the fuel delivery arranged to deliver the fuel in the same direction as the air from the nozzles.
14. A heating device comprising a fire box formed as a trough like member having a nonperforated bottom, nozzles arranged with their delivery ends within the trough, means for the continuous delivery of fuel to the trough from above said trough, means for supplying the nozzles with air under pressure, and the fuel delivery arranged to deliver the fuel in the same direction as the air from the nozzles.
15. A heating device comprising a fuel receiver having a nonperforated fuel supporting bottom surface, a combustion chamber above said receiver, nozzles arranged with their delivery ends within the receiver, means for delivering fuel from above to the receiver as it is burned therein, and means for supplying the nozzles with air under pressure.
16. A heating device comprising a fuel receiver having a nonperforated fuel supporting bottom surface, nozzles arranged with their delivery ends within the receiver means for automatically delivering fuel from above to the receiver as it is burned therein, and means for supplying the nozzles with air under pressure.
17. A heating device comprising a grateless fuel receiver, a combustion chamber above said receiver, nozzles arranged with their delivery ends within the receiver, means adapted for gravity delivery of fuel from above to the receiver as it is burned therein, and means for supplying the nozzles with air under pressure.
18. A heating device comprising a fuel receiver having a nonperforated fuel supporting surface, a blowing device centrally arranged within said receiver, a centrally arranged fuel feeding device delivering the fuel from above to the receiver as it is burned therein, and means for supplying the blowing device with air under pressure.
19. A heating device comprising a fuel receiver having a nonperforated fuel supporting surface, a blowing device centrally arranged within said receiver, a centrally arranged gravity fuel feeding device delivering the fuel from above to the receiver as it is burned therein, and means for supplying the blowing device with air under pressure.
20. A heating device comprising a fuel receiver having a nonperforated fuel supporting surface, a combustion chamber above said receiver, a blowing device arranged within said receiver, said blowing device of lesser extension than the receiver, a fuel feeding device delivering the fuel from above to the receiver, and means for supplying the blowing device with air under pressure.
21. A heating device comprising a fuel receiver having a nonperforated fuel supporting surface, a combustion chamber above said receiver, a blowing device arranged within said receiver, said blowing device of lesser extension than the receiver, a fuel feeding device arranged above said blowing device and of lesser extension than the receiver, said fuel feeding device delivering the fuel from above to the receiver, and means for supplying the blowing device with air under pressure.
22. A heating device comprising a fuel receiver having a nonperforated fuel supporting surface, a blowing device arranged within said receiver, a fuel feeding device arranged above said blowing device and delivering fuel from above to the receiver, the said blowing and fuel feeding device of lesser extension than the receiver and of about the same longitudinal extension, and means for supplying the blowing device with air under pressure.
23. A heating device comprising a fuel receiver having a nonperforated fuel supporting surface, a blowing device arranged centrally within said

receiver, a gravity fuel feeding device arranged above the blowing device and delivering the fuel from above to the receiver as it is burned therein, the blowing and fuel feeding device of lesser extension than the receiver and of about the same longitudinal extension, and means for supplying the blowing device with air under pressure.

24. A heating device comprising a fuel receiver having a non-perforated fuel supporting surface, nozzles arranged with their delivery ends within the receiver, means for automatically delivering fuel from above to the receiver, means for sup-

plying the nozzles with air under pressure, air passages having their mouths above the receiver, and means to supply air to said passages.

25. A heating device comprising a fuel receiver having a non-perforated fuel supporting surface, nozzles arranged with their delivery ends within the receiver, means for automatically delivering fuel from above to the receiver, means for supplying the nozzles with air under pressure, and heat controlled means to control the supply of pressure air to the nozzles.
